UNITED STATES PATENT OFFICE.

PAUL GEBHARDT AND CARL GEBHARDT, OF STRALAU, NEAR BERLIN,
GERMANY.

PNEUMATIC DEVICE FOR DRAWING OUT GRAINS AND SIMILAR GOODS.

No. 850,639.

Specification of Letters Patent.

Patented April 16, 1907.

Application filed September 24, 1906. Serial No. 336,029.

To all whom it may concern:

Be it known that we, PAUL GEBHARDT and CARL GEBHARDT, both subjects of the King of Prussia, German Emperor, and residents of Stralau, near Berlin, Kingdom of Prussia, German Empire, have jointly invented new and useful Improvements in Pneumatic Devices for Drawing out Grains and Similar Materials, of which the following is an exact specification.

Our invention has the purpose of providing devices for drawing out grains and similar goods with a mouth consisting of two concentric tubes, the jacket-tube serving for introducing air. In order to be enabled to regulate the supply of the air to the inner tube, the concentric jacket-tube of the mouthpiece is bent at its free end and dips into the material to be drawn or sucked out to form an inner nozzle, the diameter of which is smaller than that of the inner tube.

The jacket-tube permits the device to be moved up and down. Owing to this arrangement, the cross-section between the jacket-tube and the inner tube, through which the secondary air passes, can be altered by axial adjustment of both the tubes in relation to each other.

In consequence of the arrangement of the nozzle the material to be drawn out is prevented from entering the space formed between the drawing-tube and the jacket-tube, and thereby there is no possibility of obstructing the path of the air sucked off by a ventilator or fan or the like.

In order to make our invention clear, we refer to the accompanying drawing, in which our improved mouthpiece is illustrated in vertical cross-section.

a designates a jacket-tube, and b the concentric drawing-tube, the latter being connected with the conduit for leading away the grain (not shown) by means of a screw-collar d, supporting the jacketed tube b by a flange b'. For joining the jacket-tube a to the tube

b a flanged ring e is provided, secured to the mantle-tube b and carrying regulating-screws c. The regulating-screws c are arranged in a flange a' of the tube a. Between the flanged ring e and the flange a' a spring f is arranged, 50 permitting the mantle-tube a to be adjusted.

At the free end of the mantle-tube a a nozzle g is provided by turning the end of the tube inwardly and is adapted to project into the inner tube b if the jacket-tube a is adjusted in a corresponding manner by means of the regulating-screws f. The free end of the inner tube is preferably enlarged in order to be adapted to the nozzle g of the jacket-tube. The springs f have also the purpose of 60 regulating automatically the cross-section between the nozzle g and the drawing-tube b in case of drawing out heavy materials, whereby the tube a may be raised temporarily too high, thus diminishing said cross-section.

Having thus fully described the nature of our invention, what we desire to secure by Letters Patent of the United States is—

In a pneumatic device for drawing out 7 grains and similar materials, a mouthpiece consisting of two concentric tubes, the jacket-tube serving for feeding air, a nozzle formed at its free end by bending the same inwardly, the diameter of said nozzle being smaller 7 than that of the inner tube, and a flange-ring fixed to an outer tube, a flange fixed to the jacket-tube, screws for connecting both the tubes and springs to regulate the passage 8 formed between the nozzle of the jacket-tube and the free end of the inner tube, substantially as described.

In witness whereof we have hereunto set our hands in the presence of two witnesses.

PAUL GEBHARDT.
CARL GEBHARDT.
